UNITED STATES PATENT OFFICE.

ALLEN A. TIRRILL, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRICAL REGULATOR.

1,147,576.

Specification of Letters Patent.

Patented July 20, 1915.

Application filed April 1, 1915. Serial No. 18,503.

To all whom it may concern:

Be it known that I, ALLEN A. TIRRILL, a citizen of the United States, and a resident of Pittsburgh, in the county of Allegheny and State of Pennsylvania, have invented a new and useful Improvement in Electrical Regulators, of which the following is a specification, this application being for the most part a continuation of application, Serial No. 653,010, filed Oct. 5, 1911, and a substitute for forfeited application, Serial No. 752,623, filed March 7, 1913.

My invention relates to electrical regulators, and it has for its object to provide a simple and exceptionally effective regulator of the kind in which the regulation is effected by adjustment of the field excitation of a dynamo-electric machine.

The single figure of the accompanying drawing is a diagrammatic view of a system of distribution embodying my invention.

A system in connection with which the present invention may be conveniently employed comprises a main generator having an armature 1 that is connected to a suitable distributing circuit 2—3—4 and a field magnet winding 5 that is supplied with exciting current from an exciter 6. The exciter is provided with a field magnet winding 7 that is preferably shunt excited, though it may be supplied with current from any other suitable source, and in series with the said field magnet winding is a resistor 8 that is adapted to be shunted by means of coöperating stationary and movable contact terminals 9 and 10 of a relay 11 constituting a part of the regulator.

The regulator comprises, further, a stationary contact terminal 12 that is resiliently mounted, as by being supported upon the end of a plate spring 13, and a coöperating movable contact terminal 14 that is mounted near one end of a bell crank lever 15. The lever 15 is pivotally supported or fulcrumed upon the lower end of the vertical arm of another bell crank lever 16 and is actuated by an electromagnet 17, the said winding being energized from the circuit 2—3—4, as, for instance, by being connected through a transformer 18, to the conductors 2 and 3. When thus connected, it is energized in proportion to the voltage of the distributing circuit. The winding 17 is provided with a core 19 that is pivotally connected to the lever 15 and is partially counter-balanced by

an adjustable counterweight 20, the winding serving, when sufficiently energized, to raise the said core. The movements of the core 19 are preferably retarded, as, for instance, by means of a dash pot 21. The winding 17 serves to vary the distance of the contact terminal 14 from the stationary contact terminal 12 in response to variations of any selected electrical condition of the distributing circuit, which, as illustrated in the drawing, is its voltage.

The lever 16 is actuated so as to move the contact terminal 14 substantially horizontally into and out of engagement with the stationary contact terminal 12 by means of an electromagnet winding 24 having a core 25 that is drawn downwardly in opposition to a spring 27 when the winding 24 is sufficiently energized, the movements of the core 25 and the lever 16 being preferably retarded, as, for instance, by means of a dash pot 26. The retardation afforded by the dash pot 26 is preferably less than that afforded by dash pot 21, in order that the approximate regulation may be effected by the winding 24 and the fine regulation by the winding 17. With respect to the matter of the adjustments of the dash pots relative to each other, this application is not a division of application, Serial No. 653,010. The winding 24 also receives energy from the distributing circuit 2—3—4 through the transformer 18 or in any other suitable manner, and a lamp 33, or any other suitable resistor, is connected in series therewith, the said resistor being adapted to be shunted by means of coöperating stationary and movable contact terminals 34 and 35 of a relay 36. The relays 11 and 36 are provided with parallel-connected actuating windings 37 and 38, respectively, that receive energy from the exciter or any other suitable source, and the circuits of which are governed by the contact terminals 12 and 14.

It will be observed that the construction of the apparatus is such that the contact terminal 14 may be actuated independently by the windings 17 and 24, the said windings both serving to vary the distance of the contact terminal 14 from the terminal 12 in response to variations of an electrical condition of the distributing circuit, and the winding 24 serving in addition to move the contact terminal 14 into and out of engagement with the terminal 12 in accordance

with variations of the degree of its energization, which variations are caused by the engagement and disengagement of the relay contact terminals 34 and 35. Inasmuch as the degree of energization of the winding 24 also varies with the voltage of the circuit 2-3-4, it serves to effect approximate regulation alone.

- The mode of operation of the regulator 10 will be best understood from a detailed consideration thereof. When, as illustrated, the contact terminal 14 is out of engagement with the terminal 12, the relay magnet windings 37 and 38 are not energized and, 15 consequently, the contact terminals 9 and 34 do not engage the terminals 10 and 35. The shunt circuit to the resistor 8 is then interrupted and the field excitation and voltage of the exciter are diminished, followed by a diminution of the field excitation and voltage of the main generator. By 20 reason of the reduction of the voltage of the generator, the windings 17 and 24 are energized to a less degree and the contact terminal 14 is accordingly moved slightly toward the terminal 12. When the contact terminals 34 and 35 are not in engagement, the resistor 33 is included in the circuit of the magnet winding 24, with the result that 25 the winding is less strongly energized, and the spring 27 draws the contact terminal 14 into engagement with the terminal 12. The relay magnet windings 37 and 38 are thereupon energized and the relay contact members are brought into engagement. A shunt 30 circuit to the resistor is thus established, with the result that the field excitation and voltage of the exciter are increased, followed by increases of the field excitation 35 and voltage of the main generator. Then, by reason of the greater energization of the windings 17 and 24, the contact terminal 14 is moved slightly away from the terminal 12. Upon engagement of the contact terminals 34 and 35, the resistor 33 is shunted 40 and the magnet winding 24 becomes more strongly energized, with the result that the contact terminal 14 is thereby moved out of engagement with the terminal 12. 45 Since the dash pots 21 and 26 are adjusted so that the winding 24 may actuate the terminal 14 more readily and promptly than the winding 17, the former winding will effect the approximate or rough regulation, and the latter winding, coöperating 50 with the former, will effect the final or accurate regulation. The regulator continues to operate in this manner, the periods of engagement and disengagement of the contact terminals 12 and 14 varying with the 55 position of the contact terminal 14 as determined by the voltage or any other selected electrical condition of the distributing circuit, and in such manner that the 60 said electrical condition will be permitted

to vary only slightly from a uniform or required value and will be quickly brought to a condition of stability. By reason of the fact that the winding 24 receives energy from the main circuit, rather than from the 70 exciter circuit, and that its circuit is governed by the relay 36, the regulator very quickly and effectively restores the voltage or other electrical condition to its normal value. The operation of the regulator is 75 entirely independent of the exciter voltage and of the consequent delays resulting from the retardation due to the inductance of the exciter field circuit, and the regulator is also unaffected in its operation by commutation troubles of the exciter. It also 80 does not require adjustment for different exciter voltages.

While the regulator has been shown as employed for regulating in accordance with 85 variations of voltage or current, it will be readily understood that it may be adapted to meet other requirements and to regulate in accordance with variations of any other electrical condition of a circuit or system 90 without departing from the spirit of the invention. The regulator may be employed for regulating direct current machines as well as alternators.

I claim as my invention:

1. An electrical regulator comprising co-operating contact members, a lever for actuating one of said members, a winding for actuating said lever, a second lever having its fulcrum above that of the aforesaid lever and providing a fulcrum therefor, and means for actuating the said second lever. 95

2. An electrical regulator comprising co-operating contact members, a lever for actuating one of said members, a winding for actuating said lever, a second lever having its fulcrum above that of the aforesaid lever and providing a fulcrum therefor, and another winding for actuating the said second lever. 105

3. An electrical regulator comprising co-operating contact members, a lever for actuating one of said members, a winding for actuating said lever, a second lever having its fulcrum above that of the aforesaid lever and providing a fulcrum therefor, another winding for actuating the said second lever, and means for retarding the movements of the latter lever. 110

4. An electrical regulator comprising co-operating contact members, a bell crank lever having a stationary fulcrum, a second lever fulcrumed upon the other and having an arm extending in substantially the same direction as the arm of the other lever upon 125 which it is fulcrumed, one of the contact members being carried by the said arm of the second lever, and actuating means for each of said levers.

5. An electrical regulator comprising co- 130

operating contact members, a lever having a stationary fulcrum, a bell crank lever fulcrumed upon the other lever, one of the contact members being carried by one of the 5 arms of the bell crank lever, and actuating means for each of said levers.

6. An electrical regulator comprising co-operating contact members, a lever having a substantially vertical arm for actuating one 10 of said members, a second lever also having a substantially vertical arm providing a fulcrum for the aforesaid lever, and actuating means for the said levers.

7. An electrical regulator comprising co-operating contact members, a lever for actuating one of said members, a winding for actuating said lever, a second lever providing a fulcrum for the aforesaid lever, the fulcrum of one lever being located substantially 20 vertically above that of the other, and means for actuating the said second lever.

8. An electrical regulator comprising co-operating contact members, a lever for actuating one of said members, a second lever 25 providing a fulcrum for the aforesaid lever, the fulcrum of one lever being located substantially vertically above that of the other, and means for actuating each of said levers.

9. The combination with an electrical circuit and a dynamo-electric machine, of a 30 regulator for the dynamo-electric machine comprising co-operating contact members, a single winding for causing the said members to engage and disengage and the circuit 35 of which is controlled thereby, and another winding for adjusting the periods of engagement of said members in accordance with the variations of an electrical condition of the said circuit, one of said windings varying the position of the fulcrum of 40 action of the other upon the contact members.

10. The combination with an electrical circuit, of a regulator comprising co-operating contact members, actuating windings 45 therefor each of which receives current from said circuit and the circuit of one of which is controlled by the contact members, and means for retarding the effects of said windings upon the contact members, the retardation 50 of the effect of one winding being greater than that of the other winding.

11. The combination with an electrical circuit, of a regulator comprising co-operating contact members, actuating windings 55 therefor each of which receives current from said circuit and the circuit of one of which is controlled by the contact members, and means for retarding the effects of said windings upon the contact members, the retardation 60 of the effect of the winding the circuit of which is controlled by the contact mem-

bers being less than that of the other windings.

12. The combination with an electrical 65 circuit, of a regulator comprising co-operating contact members, two actuating windings therefor each of which is continuously energized in proportion to variations of the same electrical condition of said circuit and 70 the circuit of one of which is also controlled by the said contact members.

13. The combination with an electrical circuit, of a regulator comprising co-operating contact members and two actuating 75 windings therefor each of which is continuously energized in proportion to variations of the same electrical condition of said circuit, a resistor in circuit with one of said windings, and a circuit in shunt to said resistor that is controlled by the said contact members.

14. The combination with an electrical circuit, of a regulator comprising co-operating contact members, two actuating windings 85 therefor each of which is continuously energized in proportion to variations of an electrical condition of said circuit and the degree of energization of one of which is also controlled by the contact members in- 90 dependently of their effect upon the electrical condition of the circuit, and means whereby each of the said windings may cause relative movements of the said members independently of the other. 95

15. The combination with an electrical circuit, and a dynamo-electric machine that supplies energy thereto, of a regulator comprising co-operating contact members, two actuating windings therefor each of which 100 is continuously energized in proportion to variations of the same electrical condition of said circuit, a plurality of relays that are controlled by the contact members one of which in turn controls the circuit of one of 105 the said windings and the remainder of which control the field excitation of the dynamo-electric machine.

16. The combination with a dynamo-electric machine, of a regulator therefor comprising a pair of co-operating contact members, two actuating windings therefor, means whereby each of said windings may cause relative movements of said members independently of the other, a plurality of relays 115 that are controlled by the contact members, one of which in turn controls the circuit of one of the said windings and the remainder of which control the field excitation of the dynamo-electric machine. 120

In testimony whereof, I have hereunto subscribed my name this 30th day of March, 1915.

ALLEN A. TIRRILL.
